(57) **CLAIM**

The ornamental design for a pedestal scanner, as shown and described.

DESCRIPTION

FIG. 1 is a top, front, left-side perspective view of a pedestal scanner;

FIG. 2 is a bottom, back, right-side view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dot-dot-dashed broken lines depict a symbolic break in the length of a barrier on the pedestal scanner. The symbolic break lines and portion between the symbolic break lines form no part of the claimed design.

The dashed broken lines depict portions of the pedestal scanner that form no part of the claimed design. The dot-dashed broken lines represent boundaries of the claimed design and form no part of the claimed design.
